OILING SYSTEM FOR COMPRESSORS

Walter R. Freeman, Clayton, Mo., assignor to
Wagner Electric Corporation, St. Louis, Mo., a
corporation of Delaware

Application January 31, 1941, Serial No. 376,807

5 Claims. (CL 230—206)

My invention relates to compressors and more particularly to an oiling system therefor.

One of the objects of my invention is to embody in an oiling system for a compressor having a separate oil reservoir, improved control means which will permit oil to flow to the compressor and lubricate the parts thereof only when the compressor is operating to discharge compressed fluid.

Another object is to provide in a compressor oiling system of the kind referred to valve means for positively shutting off the flow of oil to the compressor whenever the compressor is either unloaded or not being actuated and to accomplish this notwithstanding compressed fluid from the compressor may be acting on the oil in the reservoir.

Other objects of my invention will become apparent from the following description taken in connection with the accompanying drawing in which the single figure is a view of a compressor system having embodied therein my invention for controlling the flow of oil to the compressor.

Referring to the drawing in detail, numeral 1 indicates a rotary compressor of well-known design having a rotor shaft 2 driven by any suitable means such as a pulley 3. In this compressor the fluid to be compressed, which in this particular instance is air, enters the compressor through the inlet 4 where it is compressed and discharged through the discharge outlet 5. The discharged compressed air passes through the check valve 6 into the conduit 7 where it is conveyed into the top of an oil reservoir 8 by means of a tube 9 extending up into the reservoir. The upper end of the reservoir is connected by a conduit 10 to the air receiver or tank 11 from which the compressed air may be withdrawn to actuate any device desired. A check valve 12 is interposed between the reservoir and the conduit 10 and prevents back flow of air under pressure into the reservoir.

The inlet of the compressor is connected by a conduit 13 to an unloading valve assembly 14 which may be of any desired construction such as, for example, that shown in the Fites application Serial No. 301,102, filed October 25, 1939, for Valve mechanism for unloading compressor. This valve assembly is adapted to be controlled by the compressed air in the receiver in order to cut oil communication from the atmosphere through the air cleaner 15 to the conduit 13 whenever the pressure in the receiver reaches a predetermined value say, for example, 100 pounds per square inch. A conduit 16 between said

valve assembly and conduit 10 leading to the air compressor causes said valve to be subjected to the air pressure in the receiver in order to be properly controlled. In addition to the shut-off valve in the valve assembly 14, there is also employed valve means for simultaneously venting the air reservoir to the atmosphere through the air cleaner whenever the shut-off valve is closed to unload the compressor. The conduit through which the reservoir is unloaded is shown at 17 and communicates with the reservoir at a point below the check valve 12. By venting the reservoir to atmosphere when the compressor is unloaded, the compressor will run more freely since any fluid discharged passes directly into the atmosphere instead of into a chamber having fluid under pressure therein.

Since the oil reservoir receives the discharged compressed air, the oil therein is placed under pressure whenever the compressor is operated. In order that the oil may be conveyed to the compressor bearings 18 and other moving parts, there is provided a conduit 19 which is connected to the bottom of the reservoir by a passage 20.

In accordance with my invention I provide means for properly controlling the flow of oil from the reservoir to the compressor in such a manner that the oil will flow only when the compressor is operating and compressing air. At all other times the oil is prevented from communicating with the compressor in order to conserve on the oil supply and prevent the compressor from becoming "choked" with oil. As shown in the figure, there is provided a valve casing 21 provided with chambers 22 and 23 divided by a partition 24. Carried by this partition on the side of the chamber 23 is a valve seat 25 which surrounds the end of a passage 26 in the partition for placing the conduit 19 in communication with the chamber 23 which chamber communicates with the reservoir by means of the passage 20 previously referred to. Cooperating with the valve seat 25 is a movable valve element 27 positioned in chamber 23 and normally biased onto the seat 25 by a spring 28.

The chamber 22 in the valve casing communicates at one end with the conduit 7 coming from the exhaust port of the compressor and also with the tube 9 leading to the top of the oil reservoir by way of passage 29. Positioned in the chamber 22 is a piston 30 carrying a projection 31 which extends through the partition 24 in order to engage the valve element 27. The piston has a loose fit with the wall of the chamber and is

adapted to engage the open end of the fitting 32 which connects the conduit 1 to the chamber 22 in order to block this open end when positioned at the left end of the chamber. However, when the piston is moved to the right end of the chamber, the passage 28 will be uncovered and thus permit free flow of fluid from the conduit 1 to tube 8. Also, when the piston is in the latter mentioned position, the projection 34 will engage and unseat the valve element 27.

In operation, when the compressor is not being driven the spring 29 will hold the valve element 27 seated and thereby prevent any oil from entering the conduit 19 for passage to the compressor bearings and moving parts. When the compressor is being driven and compressing air, this compressed air will be discharged through the exhaust port and the conduit 1 to act on the piston 30. This air under pressure will force the piston to the right so that it will place the passage 28 in free communication with conduit 1 and permit the compressed air to enter the top of the reservoir from where it can pass through the check valve 12 to the air receiver. The movement of the piston to the right also causes the valve 27 to be unseated against the bias of spring 28, thereby placing the conduit 19 in communication with the bottom of the reservoir to permit oil to flow to the compressor bearings and working parts. The piston will always be maintained in the right hand end of the chamber 22 whenever the compressor is discharging compressed air, due to the fact that this compressed air in flowing to the reservoir will impinge on the piston and maintain it in such position. The amount of oil being fed to the compressor through pipe 19 will only be sufficient for proper lubrication and to replace the oil being carried out of the compressor with the compressed air. The amount of oil is regulated by the size of the passage in the rotor shaft 2 through which the oil is fed to the compressor. As long as the proper level of oil is maintained in the reservoir all the oil will never be forced out of the reservoir as oil is being continuously returned to the reservoir as it is fed therefrom to the compressor.

When the air pressure in the receiver reaches the predetermined value necessary to operate the unloading valve in the valve assembly 14, the inlet to the compressor will be shut off from atmosphere and the compressor will thereby be unloaded. Simultaneously with the cutting off of the admission of air to the compressor, the oil reservoir will also be placed in communication with the atmosphere and relieve the oil reservoir of the air under pressure. As soon as the compressor discontinues discharging any appreciable volume of compressed air, the spring 28 will become effective to seat the valve element 27 since the piston 30 is no longer held by any compressed air in the position to maintain the valve 27 unseated. This seating of the valve will cut off communication between the oil reservoir and the conduit 19 and thus prevent any oil from passing to the compressor.

If the compressor should be stopped, that is no longer driven by the pulley 3 when the compressor inlet port is not shut off by means of the shut-off valve, the valve element 27 will, nevertheless, be seated, and oil will no longer be able to flow to the compressor. Under these conditions the air pressure in the oil dome is not vented to atmosphere since the compressor unloading valve was not shut off due to the fact that the air in the receiver had not reached the

predetermined value necessary for such operation. Thus it is seen that, notwithstanding the fact that air under pressure may be present in the oil reservoir and acting on the oil at the time that the compressor is no longer driven, the flow of oil will be cut off. Therefore, under all conditions except when the compressor is operating and discharging compressed air, communication between the oil reservoir and the compressor will always be cut off. Therefore, there is no possibility of too much oil being forced into the compressor when the compressor is no longer driven (rotor rotating) and there is still air under pressure in the reservoir. In prior constructions wherein the air pressure in the oil reservoir is employed to control a valve for shutting off the flow of oil, the flow of oil would not be stopped under these conditions.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In apparatus of the class described, a fluid compressor, an oil reservoir connected by a conduit with the compressor for lubricating the moving parts thereof, a conduit for conveying the exhausted compressed fluid from the compressor, a valve for cutting off the flow of oil between the reservoir and the compressor, and means comprising a movable member so associated with the fluid conveying conduit that it will be acted on and moved by the discharged compressed fluid flowing through the conduit and thereby cause the valve to be moved to open position.

2. In apparatus of the class described, a fluid compressor, an oil reservoir connected by a conduit with the compressor for lubricating the moving parts thereof, a conduit for conveying the exhausted compressed fluid from the compressor through the reservoir, a valve for cutting off the flow of oil between the reservoir and the compressor, and means for opening the valve comprising a member so associated with the fluid conveying conduit that the discharged compressed fluid will impinge thereon and cause said member to be moved to open the valve before said compressed fluid passes to the reservoir.

3. In an intermittently operated fluid compressor system having a discharge conduit and an oil reservoir for supplying the moving parts of the compressor with lubricant and which is so associated with the compressor that discharged compressed fluid acts on the oil in the reservoir to force it to the compressor, means for preventing oil from flowing to the compressor moving parts when the compressor is not operating to discharge compressed fluid and notwithstanding compressed fluid may be in the reservoir, said means comprising a valve biased to closed position and a member so associated with the discharge conduit that it will be contacted and moved by the compressed fluid when flowing through the conduit to thereby open the valve.

4. In apparatus of the class described, a fluid compressor, an oil reservoir connected by a conduit with the compressor for lubricating the moving parts thereof, a conduit for conveying the exhausted compressed fluid from the compressor, a valve for cutting off the flow of oil

between the reservoir and the compressor, and means for opening the valve comprising a chamber in the fluid conveying conduit means and having spaced openings one of which communicates with the portion of the conduit means leading from the compressor and the other of which communicates with the portion of the conduit means leading to the reservoir, and a movable member in said chamber operatively connected to the valve, said member adapted to be positioned between the two openings when the valve is closed and to be moved to a position to uncover the second opening by the force of the discharged compressed fluid and thereby open the valve.

5. In apparatus of the class described, a fluid compressor provided with an exhausted port, an oil reservoir, a receiver connected to the top of the reservoir, a casing provided with aligned

bores, conduits for connecting one of said bores to the oil reservoir and to the compressor for thereby conveying oil to the moving parts of said compressor, a valve in said bore for cutting off the flow of oil, a spring for seating the valve, conduits for connecting the other bore to the exhaust port and to the reservoir, a piston in said second bore and provided with a projection for unseating the valve, said piston when the valve is closed by the spring being so positioned as to be in the path of flow of compressed fluid from the compressor to the reservoir whereby compressed fluid from the compressor when it is operating will impinge on the piston and cause it to move the valve to open position, the valve open position of said piston being such as to permit free flow of compressed fluid from the compressor to the reservoir.
